(57) **CLAIM**

The ornamental design for a tabbed divider having a plurality of transparent display pockets, as shown and described.

DESCRIPTION

FIG. 1 is a front elevational view of a tabbed divider having a plurality of transparent display pockets of the present invention, with the pockets on the front side only;

FIG. 2 is a top edge view of thereof;
FIG. 3 is a left side elevational view thereof;
FIG. 4 is a right side elevational view thereof;
FIG. 5 is a bottom edge view thereof;
FIG. 6 is a rear elevational view thereof;
FIG. 7 is an enlarged cross-sectional view taken on lines 7—7 of FIGS. 1, 11 and 17;
FIG. 8 is an enlarged cross-sectional view taken on lines 8—8 of FIGS. 1, 11 and 17;
FIG. 9 is an enlarged cross-sectional view taken on lines 9—9 of FIGS. 1, 11 and 17;
FIG. 10 is an enlarged cross-sectional view taken on lines 10—10 of FIGS. 1, 11 and 17;
FIG. 11 is a front elevational view of a second embodiment of our invention of FIG. 1;
FIG. 12 is a top edge view thereof;
FIG. 13 is a left side elevational view thereof;
FIG. 14 is a right side elevational view thereof;
FIG. 15 is a bottom edge view thereof;
FIG. 16 is a rear elevational view thereof;
FIG. 17 is a front elevational view of a third embodiment of our invention of FIG. 1;
FIG. 18 is a top edge view thereof;
FIG. 19 is a left side elevational view thereof;
FIG. 20 is a right side elevational view thereof;
FIG. 21 is a bottom edge view thereof;
FIG. 22 is a rear elevational view thereof;
FIG. 23 is a front elevational view of a fourth embodiment of our invention of FIG. 1, with the pockets on both the front and rear sides;
FIG. 24 is a top edge view thereof;
FIG. 25 is a left side elevational view thereof;
FIG. 26 is a right side elevational view thereof;
FIG. 27 is a bottom edge view thereof;
FIG. 28 is a rear elevational view thereof;
FIG. 29 is an enlarged cross-sectional view taken on lines 29—29 of FIG. 23;
FIG. 30 is an enlarged cross-sectional view taken on lines 30—30 of FIG. 23;
FIG. 31 is an enlarged cross-sectional view taken on lines 31—31 of FIG. 23; and,
FIG. 32 is an enlarged cross-sectional view taken on lines 32—32 of FIG. 23.
